ABSTRACT OF THE DISCLOSURE

1-amino-2-nitro-4-(2'-hydroxyethyl)-methylaminobenzene, a new compound, is used to dye keratinic fibers, especially living human hair.

Substituted nitro-paraphenylenediamine products are well known as active ingredients in solutions for dyeing keratinic fibers and in particular for dyeing living hair. The alkyl and hydroxyalkyl groups are especially well known as substituents for modifying the shades which may be obtained with nitro-paraphenylenediamine itself.

The object of the present invention is to provide a new dye which is a di-substituted derivative of nitro-paraphenylenediamine. This new dye is 1-amino-2-nitro-4-(2'-hydroxyethyl)-methylaminobenzene, which has the formula:

(I)

The invention also comprises two new methods of preparing the compound according to the above formula.

The first of these methods of preparation is essentially characterized by the fact that 1-amino-2-nitro-4-methylaminobenzene is hydroxyalkylated by means of a halo-hydrin, for example. Hydroxyalkylation in the meta position of the nitro group can be effectuated in commercial quantities, without impurities, especially when using a bromohydrin.

The second method of preparation according to the invention which makes it possible to obtain the compound according to Formula I is essentially characterized by the fact that 1-acetamino-4-(2'-hydroxyethyl)-methylaminobenzene is nitrated with a sulfonic acid mixture and that the resulting product is deacetylated by means of hydrochloric acid, for example.

The invention also relates to the new dyes for keratinic fibers, and especially for human hair which utilize the composition according to Formula I and consisting of simple aqueous solutions of the said compound, preferably at an alkaline pH. Various ingredients conventionally used in hair dyeing preparations, such as organic solvents, detergents, thickening agents, and lacquers, may be added to these compositions.

Their use does not require the addition of oxidizing agents to develop the color. The time during which they should be left in contact with the hair may vary within

2

broad limits, but falls preferably between 10 and 30 minutes. The temperature at which these dyes are applied may also be varied, but in most cases they are preferably applied at room temperature. The pH of these solutions is in general between 7 and 10 and preferably between 8 and 9.5. An alkali such as plain ammonia, or an organic base such as an alkylamine, an alkanolamine, or a heterocyclic amine may be used to adjust this pH. The concentration of the dyes according to the invention may be varied, but this concentration is preferably between 0.1% and 3%. It should be noted that the new dye may be mixed with other nitro, azo or anthraquinone dyes, or any other dyes conventionally used for dyeing hair.

A further object of the present invention is to provide a new method of dyeing keratinic fibers and especially human hair, which method is essentially characterized by the steps of applying to the hair a dyeing composition comprising in solution at least one compound according to Formula I and leaving this composition in contact with the hair for from 10 to 30 minutes.

It should be emphasized that the compound according to Formula I may also be used as a base product in the organic synthesis of tri-substituted derivatives of nitro-paraphenylenediamine. The present invention therefore envisages as a particular method of using the compounds according to the invention, a process of synthesizing 1-methylamino-2-nitro-4-(2'-hydroxyethyl)-methylaminobenzene by using the compound of Formula I. This process is essentially characterized by the fact that benzene-sulfochloride is reacted with the compound of Formula I so that the former becomes attached to the unsubstituted nitrogen atom. The resulting product is treated with methyl sulfate in an alkaline medium, and the sulfonylbenzene radical fixed in the first step of the process is removed by hydrolysis in a hydrochloric acid medium.

The present invention also envisages, as a particular use for the compound according to the invention, a process of preparation which makes it possible to synthesize 1-(2'-hydroxyethyl)-amino-2-nitro-4-(2'-hydroxyethyl)-methylaminobenzene. This process is essentially characterized by the fact that chloroethyl-chloroformate is reacted with the compound according to Formula I to yield the β -chloroethyl ester of [2-nitro-4-(2'-hydroxyethyl)-methylamino]phenylcarbamic acid and this ester is then hydrolyzed with caustic potash purified by solution in alcohol.

Two methods of preparing the compound according to the invention, and its method of use in hair dyes and as a starting material for the synthesis of 1-methylamino-2-nitro-4-(2'-hydroxyethyl)-methylaminobenzene and 1-(2'-hydroxyethyl)-amino-2-nitro-4-(2'-hydroxyethyl)-methylaminobenzene will now be described, purely by way of example.

EXAMPLE 1

First method of preparing 1-amino-2-nitro-4-(2'-hydroxyethyl)-methylaminobenzene

One mol (167 g.) of 1-amino-2-nitro-4-methylaminobenzene is mixed with 1000 cm.³ of water and 60 g. of calcium carbonate. The mixture is boiled under reflux and 1.2 mols (150 g.) of glycol bromohydrin is added drop by drop, while stirring. After boiling under reflux for two hours, 1500 cm.³ of boiling water is added, and after having continued the reflux for several minutes, the mixture is filtered through a funnel for hot filtration. After cooling, the filtrate yields 161 g. of the crude product, which, after two recrystallizations in methylisobutylketone, melts at 115° C.

Analysis of end product: Calculated for C₉H₁₃O₃N₃ (percent): C, 51.18; H, 6.16; N, 19.90. Found (percent): C, 50.89-50.98; H, 6.16-6.43; N, 20.21-20.23.

3
EXAMPLE 2

Second method of preparing 1-amino-2-nitro-4-(2'-hydroxyethyl)-methylaminobenzene

(a) *First step: nitration.*—0.1 mol (21 g.) of 1-acetamino-4-(2'-hydroxyethyl)-methylaminobenzene is dissolved in 75 cm.³ of concentrated sulfuric acid, while keeping the temperature between 0° and 2° C. A sulfonitic mixture formed by adding 6.6 g. of concentrated sulfuric acid to 6.6 g. of nitric acid having a density of 1.52 is then added immediately, little by little, while stirring and keeping the temperature between 0 and 2° C. The reaction mixture is then poured over ice, and neutralized with ammonia to extract the isopropyl alcohol. After having eliminated this alcohol under vacuum 23.5 g. of crude 1-acetamino-2-nitro-4-(2'-hydroxyethyl) - aminobenzene is obtained.

(b) *Second step: deacetylation and purification.*—The acetylated derivative obtained in the first step is introduced into a mixture of 30 cm.³ of concentrated hydrochloric acid and 60 cm.³ of water. This is kept for ½ hour in a boiling water bath. A little animal black is added, the product is filtered, and after drying and cooling yields 16 g. of crystallized hydrochloride. This is dissolved in boiling water, which is rendered alkaline by adding ammonia, cooled, and on drying yields 13 g. of 1-amino-2-nitro-4-(2' - hydroxyethyl) - methylaminobenzene, which after recrystallization in chloroform, melts at 115° C.

Analysis of end product: Calculated for C₉H₁₃O₃N₃ (percent): C, 51.18; H, 6.16; N, 19.90. Found (percent): C, 51.16-51.22; H, 6.12-6.42; N, 20.03-20.03.

EXAMPLE 3

The following composition is prepared:

1-amino-2-nitro-4-(2' - hydroxyethyl) - methylaminobenzene—0.75 g.
Polyoxyether of fatty alcohol (Remcopal 21.411 sold by Paix)—5 g.
20% ammonia q.s.p.—pH=8
Water, q.s.p.—100 g.

This solution is applied to white hair and left in contact therewith for 10 minutes. The hair is then rinsed, shampooed and dried. The result is a very slightly mauve rose blond shade.

EXAMPLE 4

The following composition is prepared:

1-amino-2-nitro-4-(2' - hydroxyethyl) - methylaminobenzene—0.75 g.
1-methylamino-2-nitro-4-(β-hydroxyethyl)-methylaminobenzene—0.5 g.
Polyoxyether of fatty alcohol (Remcopal 21.411 sold by Paix)—5 g.
20% ammonia q.s.p.—pH=8
Water, q.s.p.—100 g.

This solution is applied to light chestnut hair and left in contact therewith for 10 minutes. The hair is then rinsed, shampooed and dried. A light chestnut with glints of violine results.

EXAMPLE 5

The following composition is prepared:

1-amino-2-nitro-4-(2' - hydroxyethyl) - methylaminobenzene—0.75 g.
1-(γ)-diethyl-aminopropyl)-amino-2-amino-4-nitrobenzene—0.01 g.
Polyoxyether of fatty alcohol (Remcopal 21.411 sold by Paix)—5 g.
20% ammonia q.s.p.—pH=8
Water, q.s.p.—100 g.

This solution is applied to 100% white hair and left

75

4

in contact therewith for 20 minutes. The hair is then rinsed, shampooed, and dried. A warm, slightly pearlescent blond shade results.

EXAMPLE 6

Use of 1-amino-2-nitro-4-(2'-hydroxyethyl)-methylaminobenzene to synthesize 1-methylamino-2-nitro-4-(2'-hydroxyethyl)-methylaminobenzene

(a) *First step: tosylation.*—A solution is prepared comprising 0.15 mol (31.65 g.) of 1-amino-2-nitro-4-(2'-hydroxyethyl)-methylaminobenzene in 110 cm.³ of pyridine. 0.15 mol (19.2 cm.³) of benzene-sulfochloride is added little by little, while stirring, at between 45 and 50° C. The reaction mixture is kept at 45° C. for 2 hours and then poured into a liter of ice water which contains 85 cm.³ of concentrated hydrochloric acid, thus precipitating a brown resinous product which is then redissolved in methylisobutyl-ketone. The methylisobutyl-ketone solution is then extracted, using a normal sodium hydroxide solution, and the residual solution is neutralized with hydrochloric acid. On drying, this yields 36 g. of 1-benzene sulfonylamino-2-nitro-4-(2'-hydroxyethyl) - methylaminobenzene, which, after recrystallization in alcohol, melts at 112° C.

Analysis of end product.—Calculated for C₁₅H₁₇N₃O₅S (percent): C, 51.28; H, 4.84; N, 11.96. Found (percent): C, 51.56-51.39; H, 4.69-4.94; N, 12.05-12.01.

(b) *Second step: alkylation.*—A solution containing 0.0142 mol (5 g.) of the product obtained in the first step in 65 cm.³ of 0.5 N sodium hydroxide is prepared. To this solution, 0.032 mol (3 cm.³) of methyl sulfate is added, while keeping the temperature between 25 and 30° C. The reaction mixture is left for two hours at this temperature, and after cooling and drying, yields 4 g. of 1-(benzene sulfonyl)-methylamino - 2-nitro-4-(2'-hydroxyethyl)-methylaminobenzene. 50 cm.³ of 0.5 N sodium hydroxide is added to this product, while stirring, to eliminate any of the starting product which has not reacted. The product is then dried, washed with water, and recrystallized in a mixture of 75% ethyl acetate and 25% petroleum ether, yielding 3.6 g of the pure product, which melts at 116° C.

Analysis of end product.—Calculated for C₁₆H₁₉N₃O₅S (percent): C, 52.60; H, 5.20; N, 11.50. Found (percent): C, 52.87-52.70; H, 5.44-5.26; N, 11.43-11.63.

(c) *Third step: hydrolysis.*—A solution of 0.028 mol (10.22 g.) of the product obtained in the first step in 25 cm.³ of concentrated hydrochloric acid mixed with 5 cm.³ of water is heated for an hour in a boiling water bath. After cooling and dilution, the solution is neutralized with sodium hydroxide and on drying yields 5.1 g. of 1-methylamino-2-nitro-4-(2'-hydroxyethyl) - methylaminobenzene, which is practically pure, and melts at 94° C.

Analysis of end product.—Calculated for C₁₀H₁₅O₃N₃ (percent): C, 53.33; H, 6.67; N. Found (percent): C, 53.71-53.74; H, 6.46-6.93.

EXAMPLE 7

Use of 1-amino-2-nitro-4-(2'-hydroxyethyl)-methylaminobenzene to synthesize 1-(2'-hydroxyethyl)-amino-2-nitro-4-(2'-hydroxyethyl)-methylaminobenzene

(a) *First step: producing an ester.*—0.1 mol 21.1 g.) of 1 - amino - 2 - nitro-4-(2'-hydroxyethyl)-methylaminobenzene in 180 cm.³ of methyl-isobutyl-ketone. 0.05 mol (7.15 g.) of chloroethylchloroformate dissolved in 20 cm.³ of methyl-isobutyl-ketone is introduced into this solution, little by little, under reflux, and while stirring. The solution is boiled under reflux for three hours, after which it is cooled and dried, yielding 12.2 g. of the starting product in the form of the hydrochloride. The filtrate is evaporated under vacuum and yields 16.5 g. of the chloroethyl ester of [2 - nitro-4-(2'-(hydroxyethyl)-methylamino]-phenylcarbamic acid.

(b) *Second step: hydrolysis.*—The ester obtained in the first step is dissolved in 135 cm.³ of a solution of caustic potash in alcohol containing 110 g. of potash per liter. This solution is heated to reflux for two hours, and then cooled and poured into 600 cm.³ of ice water. This is then extracted with methyl-isobutyl-ketone and the solvent evaporated under vacuum. The yield is 11 g. of 1-(2'-hydroxyethyl)-amino-2 - nitro-4-(2'-hydroxyethyl)-methylaminobenzene, which, after recrystallization in benzene, melts at 99° C.

Analysis of end product.—Calculated for C₁₁H₁₇N₃O₄ (percent): C, 51.76; H, 6.66; N, 16.47. Found (percent): C, 51.26-51.61; H, 6.66-6.68; N, 16.27-16.53.

It will of course be appreciated that the methods of producing and using the products which have just been described have been given purely by way of example, and may be modified as to detail without thereby departing from the basic principles of the invention.

What is claimed is:

1. 1 - amino-2-nitro-4-(2'-hydroxyethyl)-methylamino-benzene.
2. A composition for dyeing keratinic fibers comprising dyeing amounts of the compound of claim 1 in an aqueous solution having a pH between 7 to 10.
3. A composition as claimed in claim 2 in which the concentration of said compound lies between 0.1% and 3% inclusive.
4. The method of dyeing keratinic fibers which comprises the steps of applying the composition claimed in

claim 2 thereto, and leaving said composition in contact with said fibers for between 10 and 30 minutes, inclusive.

5. The method of claim 4, wherein said keratinic fibers are live human hair.
